(57) **CLAIM**

The ornamental design for a towable camper trailer body, as shown and described.

DESCRIPTION

FIG. 1 is a perspective view of a towable camper trailer body, showing our new design;

FIG. 2 is a front right perspective view thereof;

FIG. 3 is a right side elevational view thereof;

FIG. 4 is a left side elevational view thereof;

FIG. 5 is a front end elevational view thereof;

FIG. 6 is a rear end elevational view thereof;

FIG. 7 is a top plan view thereof; and,

FIG. 8 is a bottom plan view thereof.

The broken line showing of side windows, a rear door window, a side panel, a rear panel, a side electrical receptacle, and a rear handle in the figures illustrates environmental structure only and forms no part of the claimed design.
